CLAIM

The ornamental design for a heat moisture exchanger as shown and described.

DESCRIPTION

FIG. 1 is a top side perspective view of a heat moisture exchanger.

FIG. 2 is a top view of the heat moisture exchanger of FIG. 1.

FIG. 3 is a bottom view of the heat moisture exchanger of FIG. 1.

FIG. 4 is a front view of the heat moisture exchanger of FIG. 1.

FIG. 5 is a rear view of the heat moisture exchanger of FIG. 1.

FIG. 6 is a bottom side perspective view, showing the heat moisture exchanger of FIG. 1.

FIG. 7 is a bottom front perspective view, showing the heat moisture exchanger of FIG. 1.

FIG. 8 is a top front side perspective view, showing the heat moisture exchanger of FIG. 1.

FIG. 9 is an exploded view of the heat moisture exchanger; and,

FIG. 10 is an exploded view of the invention with the unclaimed porous media.

The broken lines shown in the drawings are for purposes of illustrating portions of the Heat moisture exchanger and form no part of the claimed design.
